ABRASIVE CUTOFF MACHINE

Leo L. Vadnais, St. Paul, Minn., assignor to Herzog Iron Works, Inc., St. Paul, Minn., a corporation of Minnesota

Application May 10, 1944, Serial No. 534,880

2 Claims. (Cl. 51—98)

This invention relates to machines for cutting materials wherein the cutting operation produces considerable heat and the material being cut is subjected to considerable expansion because of the heat.

The invention is particularly adaptable to machine tools known as cut-off machines wherein work such as metal stock is fed into cutting position and where the cutting position is determined by a stop device which is adapted to be engaged by the work. One such machine is known in the trade as an abrasive cut-off machine which utilizes a thin disc of abrasive material which is rotated rapidly to cut through stock such as metal bars and rods. The abrasive discs are relatively thin and incapable of withstanding any great amount of strain or distortion.

It has been found that when a piece of metal stock such as a bar rod or pipe is placed upon a support and moved into engagement with a stop device positioned to determine the size of the piece to be cut off there is considerable expansion of the metal due to the heat generated by the abrasive disc. Frequently pieces are cut from relatively long rods or bars and when the heat produced in the cutting operation expands the metal the weight of the bar and the fact that it is held in position by a stop will cause the expanding metal to close in against the sides of the cutting disc with a bending action and the disc will break.

It is a general object of the invention to provide means for compensating for the expansive action of the heated work piece so that there will be no tendency for the cutting disc to bind and break.

The above and other objects and advantages of the invention will more fully appear from the following description made in connection with the accompanying drawing, wherein like reference characters refer to the same parts throughout the views, and, in which:

Fig. 1 is a front elevational view of a cut-off machine having my invention incorporated therewith;

Fig. 2 is a side elevation of the machine;

Fig. 3 is an enlarged fragmentary detail partially in section and partially in front elevation; and

Fig. 4 is an enlarged fragmentary top view of the stop device.

In Figs. 1 and 2 there is shown a cut-off machine having a base 5 which is adapted to be supported in any suitable manner. At the rear of the base 5 is a bracket 6 adapted to pivotally sup-

port a motor mounting 7 having lugs 8. A pivot shaft 9 extends through the bracket 6 and the lugs 8. The motor mounting 7 has an electric motor 10 suitably secured thereto. The mounting 5 7 has a forwardly extending arm 11 to which is connected a casing 12 which serves as a housing for a belt 13 driven by a pulley 14 on the motor shaft 15. The forward end of the housing 12 has a countershaft 16 journaled therein and 10 extending outwardly from one side thereof. The countershaft 16 also extends through the forward end of the motor mounting extension 11. As viewed in Figs. 1 and 3, the countershaft 16 has on its left end an abrasive disc 17, the shaft 16 and disc 17 being driven by the belt 13 which moves over a pulley 18 on said countershaft 16. A suitable guard indicated generally at 19 is provided to shield the abrasive disc 17 and said shield is provided with a work receiving cut-out 20 at its 15 20 medial lower portion.

An operating handle 21 extends forwardly from the housing 12 and by means of the handle the housing 12 and abrasive wheel 17 are adapted to be moved upwardly and downwardly about 25 the pivot pin 9 which connects the motor support 7 to the bracket 6 on the base 5. As best viewed in Fig. 2 the motor is mounted in an off-balance position so that the housing 12 and abrasive wheel 17 normally will lie in upwardly spaced relation 30 to the base 5. The details of the foregoing mechanism are conventional and a structure of that general type is produced by the Delta Manufacturing Company of Milwaukee, Wisconsin.

Mounted on the base 5 are guide rails 22 and 35 23 which lie at either side of the abrasive cut-off disc 17. As viewed in Figs. 1 and 3, I provide a stop element 24 which is pivotally connected to bracket 26 movably secured to the guide rail 23 by means of thumb screws 27. The left hand 40 end of the stop member 24 constitutes a head 28 having a downward extension as shown in Figs. 1 and 3 and having an end surface 29 which is closer to the pivot 25 at its lower portion and is spaced progressively further from the pivot 25 as said surface 29 approaches the top of the head 28.

Mounted on casing 12 is a bracket 30 which has a portion 31 extending above and parallel to the guide rail 23. An arm 32 extends downwardly from the bracket arm 31 and said arms 31 and 32 are slotted as indicated at 33 and 34 to receive a nutted bolt 35. By reason of the slots 33 and 34 the arm 32 can be adjusted longitudinally and vertically relative to the bracket arm 31. The lower end of the arm 32 is bent

outwardly as shown at 32a in Fig. 2 and just above the bent portion is a stop engaging block 36. The work to be cut is shown as a metal rod 37. It is adapted to be fed to the abrasive cutting disc 17 from left to right. The bar is placed upon the base 5 and against the guide rail 22 and then pushed to the right until the end of the rod 37 engages the surface 29 on the stop member 24. The stop, of course, is positioned so that the abrasive disc 17 will cut off a desired length of the rod 37. With the rod of metal stock in position for cutting the abrasive disc is swung down into contact with the rod and the cutting operation is commenced. As the cutting proceeds and the disc 17 passes downwardly through the rod 37 the contact block 36 on the downwardly extending arm 32 will come into engagement with the stop member 24 on the right hand side of the stop pivot bolt 25 as best indicated in Fig. 3. This will cause the work engaging head on the stop member 24 to rise out of engagement with the end of the rod or bar 37. The device is so adjusted that the abrasive wheel 17 will have cut into the rod 37 sufficiently to produce the remainder of the cut at the desired point but the rod is free to expand longitudinally under the influence of heat generated in the cutting operation.

The above described shape of the surface 29 on the stop 24 is designed to permit proper release or disengagement from the rod 37 even though rods of different widths might be used.

It will, of course, be understood that various changes may be made in the form, details, arrangement and proportions of the various parts without departing from the scope of my invention.

What I claim is:

1. In a cut-off machine having a movable cutter and a work support relative to which said cutter can be shifted, a pivoted stop device for determining the position of work on said support and relative to said cutter, said stop device having a work engaging surface disposed progressively inwardly toward the pivotal axis of said stop device, and a stop actuator for shifting said stop device about its axis and responsive to movement of said cutter.

2. In a cut-off machine having a movable cutter and a work support to which said cutter can be shifted, a stop device for determining the position of the work on said support and relative to said cutter, said stop device being movable toward and away from said support and work lying thereon, said stop device having a work engaging surface disposed progressively downwardly and away from the adjacent point of location of said work, and a stop actuator for shifting said stop device toward and away from said work support and responsive to movement of said cutter.

LEO L. VADNAIS.
